9769X

J. Gay,

No Printed Specification Available

Wood Planing Machine.

Patented June 25, 1836.

6/25/1836 9769x

June 25, 1836

Copy of Plan of Little Potato

Little Potato

The following is a copy of the Plan I had in making a part of the same, containing a description of the roads, the property, and of the buildings, and also the machines for plowing, sowing, planting, and harvesting.

It is to be observed that the property is divided into three distinct parts, the first being the property of the Indians, the second of the Indians, and the third of the Indians. The property of the Indians is divided into three distinct parts, the first being the property of the Indians, the second of the Indians, and the third of the Indians. The property of the Indians is divided into three distinct parts, the first being the property of the Indians, the second of the Indians, and the third of the Indians.

The property of the Indians is divided into three distinct parts, the first being the property of the Indians, the second of the Indians, and the third of the Indians.

The property of the Indians is divided into three distinct parts, the first being the property of the Indians, the second of the Indians, and the third of the Indians.

The property of the Indians is divided into three distinct parts, the first being the property of the Indians, the second of the Indians, and the third of the Indians.

The property of the Indians is divided into three distinct parts, the first being the property of the Indians, the second of the Indians, and the third of the Indians.

The property of the Indians is divided into three distinct parts, the first being the property of the Indians, the second of the Indians, and the third of the Indians.

The property of the Indians is divided into three distinct parts, the first being the property of the Indians, the second of the Indians, and the third of the Indians.

The property of the Indians is divided into three distinct parts, the first being the property of the Indians, the second of the Indians, and the third of the Indians.

The property of the Indians is divided into three distinct parts, the first being the property of the Indians, the second of the Indians, and the third of the Indians.

The property of the Indians is divided into three distinct parts, the first being the property of the Indians, the second of the Indians, and the third of the Indians.

The property of the Indians is divided into three distinct parts, the first being the property of the Indians, the second of the Indians, and the third of the Indians.

The property of the Indians is divided into three distinct parts, the first being the property of the Indians, the second of the Indians, and the third of the Indians.

6/25/1836

9769X

6/25/1836

9769X

W. W. Phelps

2000 0000

Franklin Roosevelt

10

1871